UNITED STATES PATENT OFFICE.

LEE E. ALING, OF SUGARCREEK, OHIO.

CENTRIFUGAL SWITCH.

Application filed December 1, 1924. Serial No. 753,359.

This invention relates to automobile signals, and more particularly to an electric signal, adapted to be automatically operated at different speeds of the machine.

In carrying out the invention, it is my purpose to utilize the governor associated with the speedometer shaft, the governor having associated therewith a movable contact designed to cooperate with fixed contacts when the vehicle is travelling at different predetermined speeds, and thus call into use one or the other of a pair of signals, one constituting a "Slow" signal and the other a "Stop" signal.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view partly in section showing the position of the movable contact when it is used in conjunction with one of the fixed contacts to operate one of the signals.

Figure 2 is a sectional view taken on line 2-2 of Figure 1.

Figure 3 is a sectional view taken on line 3-3 of Figure 1.

Figure 4 is a sectional view taken on line 4-4 of Figure 1.

Figure 5 is a sectional view taken on line 5-5 of Figure 1.

Figure 6 is a diagrammatic view.

Figure 7 is a view in elevation of the signals proper.

Referring to the drawings in detail, 10 and 11 represent slow and stop signals, which are adapted to be arranged on some appropriate part of the automobile, and electrically operated as the occasion requires. These signals may be two separate and distinct signals although the signals are preferably constructed as shown in Figure 7, wherein use is made of a single casing 10 divided by a partition 12 into upper and lower compartments, each of which being adapted to be provided with an electric light bulb. The end wall of the casing is pro-

vided with the word Slow above the partition 12, while the same wall is provided with 55 the word Stop beneath the partition 12, so that either compartment can be selectively illuminated, to call into use either of the signals mentioned.

As above stated, these signals are adapted 60 to be automatically operated at different predetermined speeds of the vehicle, and for this purpose, I employ a governor indicated at 13, and which governor is mounted upon an appropriate part of the shaft 14 which connects the speedometer with the running gear of the vehicle in the usual manner. This governor is arranged to operate in a suitable casing 15 which is also adapted to be mounted on some appropriate part of the vehicle, 70 and in which casing is arranged spaced pairs of fixed contacts, one pair being used with each of the signals above referred to. This structure is more clearly illustrated in Figure 6, wherein it will be noted that the fixed 75 contacts 16 of one pair are connected in circuit with the bulb 17 of the slow signal, while the fixed contacts 18 of the other pair are connected in circuit with the bulb 19 of the stop signal. Now, cooperating with 80 these fixed contacts is a transverse arm 20 which is mounted on the collar forming part of the governor 13 and consequently adapted to move toward and away from the fixed contacts incident to the movement of the 85 collar 21 at different speeds of the vehicle. As shown in Figure 1, the arm 20 projects an appreciable distance beyond the fixed contacts and slides in suitable guides 22 arranged within the casing 15, and which 90 guides 22 prevent the arm 20 from turning with relation to the shaft 14. The arm 20 carries a pair of movable contacts 23 and 24 respectively, the former being arranged upon the arm to cooperate with the fixed contact 16, while the latter is mounted upon the arm to cooperate with the fixed contacts 18. The fixed contacts 16 are considerably longer than the fixed contacts 18, so that when the arm 20 is lowered upon the shaft 100 14, the movable contact 23 will engage the fixed contacts 16 to operate the slow signal 10 independently of the stop signal 11 inasmuch as the contact 24 is still spaced above the contacts 18. In other words, when the 105 vehicle is travelling at an average speed of

approximately eighteen miles or better, the governor 13 holds the arm 20 spaced above both pairs of fixed contacts, and consequently neither of the signals can be operated. But, just as soon as the speed of the machine is reduced to approximately twelve or fifteen miles an hour, the governor 13 lowers the arm 20 on the shaft 14 to a position where the contacts 23 carried by said arm engages the fixed contacts 16, thereby automatically operating the slow signal 10. When the speed of the machine is further reduced, say to approximately eight miles or ten miles an hour, the arm 20 is further lowered upon the shaft 14 to a position wherein the contact 24 is brought into engagement with the fixed contacts 18, thus operating the stop signal 11. During this movement of the arm 20, the contact 23 is moved downwardly between the contacts 16 to a position where it is free of said contacts, so that the slow signal 10 is extinguished or rendered inoperative about the same time that the stop signal is called into use in the manner above described.

While it is believed that from the foregoing description, the nature and advantages of the invention will be readily apparent, I desire to have it understood that I do not limit myself to what is herein shown and described, and that such changes may

be resorted to when desired as fall within the scope of what is claimed.

Having thus described the invention, I claim:

In a circuit closer, a casing, a shaft journaled therein, a pair of spaced parallel fixed contacts rising from the bottom of the casing at each side of the shaft, one pair of contacts being longer than the other pair, a pair of spaced parallel guides rising from the bottom of the casing in juxtaposition with each pair of said contacts, and extending an appreciable distance above the latter, a governor arranged on the shaft, a collar slidably mounted thereon, a contact arm carried by the collar and arranged to slide between both pairs of guides and prevent casual rotation of said contact arm, and said arm having intermediate portions adapted to be moved into engagement with one or the other pair of fixed contacts at different predetermined speeds of the shaft, the free ends of each pair of fixed contacts being offset toward each other to engage said arm, and having their body portions spaced apart a distance greater than the width of said arm, whereby the spaced pairs of fixed contacts are used singly with said arm.

In testimony whereof I affix my signature.

LEE E. ALING.
